REFRIGERATOR

Harry L. Merrill, Nashua, N. H., assignor to
Harder Refrigerator Corporation, Cobleskill,
N. Y., a corporation of New York

Application February 1, 1937, Serial No. 123,356

8 Claims. (Cl. 62—46)

5 My invention relates to refrigerators and particularly to improvements in refrigerators of the type having a transverse partition therein subdividing the interior of the refrigerator cabinet into an ice compartment above and a storage compartment below and in which the air to be cooled flows upwardly at the sides of the refrigerator through openings in the partition and is then deflected laterally underneath the ice, and 10 finally flows downwardly into the storage compartment through a central opening in said partition. My invention also relates to improvements in grids or ice supports for refrigerators of the above type comprising a central element 15 and similar side elements which cooperate with the central element to form the grid.

In my Letters Patent #2,062,139 and my co-pending application Serial No. 102,499 filed September 25, 1936, which relate to refrigerators of the above type, I have shown the central opening in the partition bridged by an inverted U-shaped element having a flat top upon which the ice rests. The air streams flowing towards each other in opposite directions under the side elements of the grid meet beneath the inverted U-shaped element and then flow downwardly through the central opening in the partition.

In refrigerators in which the air circulates as above described, the temperature of the air as 30 it rises upwardly at the sides of the compartment and passes through the so-called warm air ducts or passages at the sides of the transverse partition is relatively high, probably of the order of about 50° F. After it has passed beneath the grid and reached a point adjacent the central opening in the partition, its temperature has fallen appreciably and is probably of the order of about 41° F. The ice on the grid to which the heat from the air is transferred is about 32° F., 35 and hence the temperature differential between the ice and the air is of the order of about 18° F. at the sides of the grid and about 9° F. as it approaches the center. Since the rate of heat transfer from air to ice, and hence the rate of ice meltage, varies with the temperature differential aforesaid, the ice tends to melt more rapidly at the sides than at the center with the result that the ice block may recede somewhat from the surface of the grid at the sides and thus, being 40 supported at and about the center only, may tend to swing on the grid.

I find that this may be overcome either by so 45 designing the center of the grid that it will, so to speak, engage the bottom of the ice, or by 50 providing a grid of such design that the rate of

heat transfer from air to ice in the central portion thereof is comparatively high, or preferably by a combination of both these features.

One of the objects of my present invention is to provide an improved type of central element which will not only increase the rate of air circulation in the refrigerator but will also effect an increased chilling of the air so that temperatures somewhat below those now attainable in the refrigerators of the foregoing patent and application may be maintained in the storage compartment. Another object is to provide an improved type of side element which may be used in co-operation with my new central element.

With these objects in view, my invention includes the novel elements and the combinations of elements described below and illustrated in the accompanying drawings in which—

Fig. 1 is a perspective view of my improved type of central grid element;

Fig. 2 is a fragmentary perspective view of a modified type of central element;

Fig. 3 is a transverse section of the element shown in Fig. 1;

Fig. 4 is a fragmentary plan view of my central element showing the drainage opening in the back thereof;

Fig. 5 is a perspective view of an improved type of side element;

Fig. 6 is a fragmentary perspective view of a side element of the type shown in my patent and co-pending application aforesaid but which may be used with my modified type of central element shown in Fig. 2;

Fig. 7 is a fragmentary sectional elevation of a refrigerator showing how my improved side element illustrated in Fig. 5 is combined with the improved central element shown in Fig. 1 to form the ice support;

Fig. 8 is an end view of a modified form of central element;

Fig. 9 is a fragmentary side view of the element shown in Fig. 8;

Fig. 10 is a fragmentary perspective view of a modified form of side element;

Fig. 11 is a fragmentary section of Fig. 10 in the plane 11—11;

Fig. 12 is a section similar to Fig. 11 showing a modification;

Fig. 13 is a fragmentary section of Fig. 10 in the plane 13—13;

Fig. 14 is a fragmentary plan view of the side element shown in Fig. 10;

Fig. 15 is a fragmentary cross section of my refrigerator looking from front to back and show-

ing a modification of the type shown in Fig. 7; and

Fig. 16 is a fragmentary cross section taken at right angles to that shown in Fig. 15.

5 In the devices of my Letters Patent and my co-pending application aforesaid, I find that there is some tendency for the flow of air to be retarded in the zone of confluence of the two side streams where they meet beneath the inverted 10 U-shaped central grid element. In the refrigerator of the present invention, I have overcome this retardation of the air flow and "pocketing" of air under the central element by so forming said element as to deflect the counter-flowing side 15 streams downwardly towards the central opening in the partition before permitting them to intermingle, and I have also increased the efficiency of the refrigerator by forming this central element of a high heat-conducting metal, such as 20 aluminum, and in the shape of a trough which will be substantially solidly filled with ice at all times. The efficiency of the refrigerator may be further increased by forming the side grid elements also of a high heat-conducting metal and 25 in the form hereinafter described.

Referring to the drawings, 1 represents generally my improved central element which preferably comprises a sheet of aluminum bent into the form of a V-shaped trough, as shown at 2, 30 and which extends substantially from the front to the back of the refrigerator cabinet. Soldered, riveted or otherwise secured, as shown at 3, to the ends of the V-shaped trough are vertically depending supports 4 which rest upon the transverse partition 5, as shown in Fig. 7. The partition 5 is to be understood as extending from the interior front to the interior back of the refrigerator cabinet 6. At the sides, openings or air ducts 7 are provided for the upflow of warm air from the storage compartment, and a central opening 8 is provided in the partition for the downflow 40 of cold air.

At the top, the sides of the V-shaped trough shown in Fig. 1 are bent outwardly to form substantially horizontal lips 9 and 10 which cooperate with the side elements of the grid as described below. In order to prevent condensation on the under side of the central element from dripping through the opening 8 into the storage compartment, I provide beneath the V, and slightly spaced therefrom, a shallow, V-shaped gutter 11 which is provided at the rear end with an opening 12 (see Fig. 4) through which the water collecting therein is discharged on top of the back portion 55 of the partition and flows into the discharge pipe 13. The partition is also preferably downwardly inclined from the sides towards the central opening and slightly inclined from the front to the rear of the cabinet in order to provide drainage 60 toward the discharge pipe 13. Secured to the opposite, inner sides of the cabinet and just above the warm air ducts 7 are angles 14 upon which the outer ends of the side elements of the grid are supported, as shown at 15.

65 While my central grid element may be used with various types of side elements, and particularly those disclosed in my Letters Patent and co-pending application aforesaid, a fragmentary portion of one of which is shown at 16 in Fig. 6, 70 I prefer to use side elements of the type shown in Figs. 5, 10, 11, 12, 13 and 14, and represented generally by the numeral 17. These elements are preferably of rather heavy aluminum and formed by extruding the metal from a die, or by casting. 75 They comprise smooth, plate-like, upper surfaces

18 having a plurality of depending fins or heat conductors 19 integral therewith. These conductors may be of uniform depth, as shown in Figs. 5, 7, 10, 11 and 15, or they may increase in depth from the sides of the refrigerator towards the central opening 8, as shown at 19' in Fig. 12, thus providing heat transfer surfaces of greater area in those zones where the temperature differential between the air and ice is reduced. While it is to be understood that my invention is not limited to side grid elements of any particular dimensions, I have found that, for ordinary household refrigerators, very satisfactory results are obtained by making the fins 19 from 1 $\frac{1}{8}$ " to 1 $\frac{1}{2}$ " deep and spacing them about $\frac{3}{4}$ " on centers. The upper surfaces 18 of the side elements extend somewhat beyond the both ends of the fins, as shown at 20 and 20' in Figs. 5, 11 and 12, to form overhanging ledges. The ledges 20 rest on the angles 14, as shown at 15. Adjacent the central element, the side elements may be formed with channels 21 therein, as shown in Figs. 5 and 7, which are adapted to fit over the lips 9 and 10 on the central element. Thus, the side elements described above are supported at one 25 end on the angles 14 and at the other end on the central element, and at such an elevation that the bottoms of the heat-conducting fins 19 are slightly spaced above the top of the partition, as shown at 22 in Fig. 7.

30 Where side elements of the type shown in Fig. 6 are used, a modified type of central element, such as that shown in Fig. 2, is employed. In this case, the cross section of the central element may be said to approximate the letter M in form. 35 The bottoms 23 of the vertical legs 24 rest on the partition at opposite sides of the central opening 8 and the vertical sides 24 of the M are provided with approximately triangular openings 25 arranged to register with the passages 26 underneath the V-shaped grid shown in Fig. 6.

40 Where it is desired to support the ice rack independently of the partition, the side elements 17 may be formed with overhanging ledges 27, at the sides, as shown in Fig. 10, which are adapted 45 to rest upon angles 28 secured to the interior back and front of the cabinet 6, as shown in Fig. 16. In this case the central element may be supported independently of the partition 5 by bent angles 29 (see Fig. 15) secured to the interior front and back of the cabinet. Where the central element is thus supported, the elements 4 shown in Fig. 1 which are designed to rest on the partition 5 are unnecessary.

45 Where the central elements is M-shaped, as shown in Figs. 2, 8 and 9, and is used with the side elements shown in Fig. 10, the openings 25 (see Fig. 9) in the legs of the M are preferably 50 rectangular and disposed to register with the air passages between the depending fins 19.

55 The type of side element shown in Figs. 10, 11 and 12 is designed to abut the side of the central element, as shown at 30 in Fig. 15, and is provided with an upturned lip 31 forming a curb or stop for water flowing downwardly towards the 65 central element. In the type of side element shown in Fig. 7 the web 32 of channel 21 serves as a water-stop. Adjacent the water-stop, the side elements are provided with openings 33 (see Figs. 11, 12 and 14) adapted to permit water to 70 pass therethrough to the partition 5 and thence to the drain pipe 13.

75 The side elements having the V-shaped valleys therein and illustrated in Fig. 6, may be formed either of aluminum or galvanized iron or steel,

but the elements shown in Figs. 5 and 10 are of aluminum as is also the central element 1.

In operation, warm air from the storage compartment flows upwardly through the ducts 7 at the sides of the refrigerator and thence, substantially horizontally between the partition and the side grid elements toward the central opening 8. Heat from the air circulating beneath the side elements of the grid is absorbed by contact 10 of the air with the lower side of said elements and with the fins 19 depending therefrom.

When a block of ice is first placed in the refrigerator, it is supported at its ends only, which rest upon the side elements of the grid near the 15 sides of the refrigerator, while the central bottom portion of the ice block is considerably above the central portion of the grid. However, as the bottom end portions of the ice melt away the ice block settles downwardly and the area of the 20 bottom of the ice in contact with the top of the grid becomes progressively greater until the V-shaped channel in the central element becomes substantially solidly filled with ice. The two 25 streams of air flowing under the side elements and in opposite directions toward the central opening impinge against the sides of the central element and, since these are inclined downwardly toward the central opening, the air is not only further chilled by coming in direct contact with 30 the ice filled central element but is also deflected downwardly toward and through the opening 8.

By using an aluminum grid throughout it is possible to maintain temperatures in the storage compartment much lower than is possible with 35 the use of other metals although it is to be understood that in the cheaper types of construction galvanized iron may be used in the side grid elements of the type shown in Fig. 6.

What I claim is:

40 1. A refrigerator comprising a cabinet, a transverse partition therein dividing said cabinet into an ice compartment above and a storage compartment below; said partition being provided with a central opening therein for the downflow 45 of cold air and being spaced from opposite sides of said refrigerator to provide openings for the upflow of warm air; and an ice support above said partition and cooperating therewith to form passages for the flow of air from said side openings towards said central opening; the central zone of said ice support above the central opening in said partition comprising a metal trough 50 adapted to be filled with ice and having the sides thereof extending downwardly into the path of the air streams emerging from said passages, whereby to deflect said air streams towards said central opening.

2. In an ice refrigerator the combination with a cabinet having a partition extending from the 60 front to the back thereof and subdividing the interior of said cabinet into an ice compartment above and a storage compartment below; said partition being provided with a central opening for the downflow of cold air and being spaced 65 from the sides of said cabinet to provide openings for the upflow of warm air; of an ice rack above said partition and comprising three separate elements whereby it is readily removable from said cabinet; said elements including two 70 similar side elements having comparatively deep, V-shaped valleys therein and cooperating with said partition to form passages for the flow of air from said side openings towards said central opening, and a central element extending across 75 the space between said side elements and posi-

tioned over the central opening in said partition; said central element being formed with a comparatively deep valley therein running in a direction at right angles to the valleys in the side elements. 5

3. An ice support for a refrigerator, comprising a central, trough-like, portion adapted to be filled with ice and formed of metal having high heat conductivity, and a portion at either side of and cooperating with said central portion 10 comprising a metal plate having high-heat conductivity and having a plurality of fins integral therewith and depending from the bottom thereof; the bottom of said trough-like portion depending substantially below the level of the top 15 of those portions of said fins which are adjacent thereto.

4. In an ice refrigerator the combination with a cabinet having a partition extending from the front to the back thereof and subdividing the 20 interior of said cabinet into an ice compartment above and a storage compartment below; said partition being provided with a central opening for the downflow of cold air and being spaced from the sides of said cabinet to form openings 25 for the upflow of warm air; of an ice rack above said partition and comprising a central element and two similar side elements cooperating therewith and with said partition to form passages for the flow of air between said side openings and 30 said central opening; said side elements comprising aluminum plates having a plurality of heat conducting fins depending therefrom into said air passages; and said central element being positioned over said central opening and 35 comprising a trough-like element of aluminum having the sides of the trough extending downwardly into the path of the air streams emerging from said passages whereby to deflect said air streams downwardly towards said central 40 opening.

5. A refrigerator comprising a cabinet, an ice support therein subdividing the interior of said cabinet into an ice compartment above and a storage compartment below, the central zone of 45 said support comprising means forming a comparatively deep trough adapted to be substantially solidly filled with ice and extending in a direction from front to rear of said cabinet, and the side zones of said support being downwardly 50 inclined towards said central zone and comprising metal plates of high heat conductivity having a plurality of heat conducting fins depending therefrom; and a partition, provided with a central opening therein and spaced from the interior sides of said cabinet, below and cooperating with the plates forming the side zones of 55 said ice support to form passages for the flow of air from the sides of said cabinet towards said central opening. 60

6. In an ice refrigerator of the character described, an ice support comprising three separable elements, including a central and two similar side elements, whereby it is readily removable from said refrigerator; the upper ends 65 of said side elements adjacent said central element being supported thereon.

7. A refrigerator comprising a cabinet, a transverse partition therein subdividing the interior of said cabinet into an ice compartment 70 above and a storage compartment below; said partition being provided with a central opening therein for the down flow of cold air and being spaced from opposite sides of said refrigerator to form openings for the upflow of warm air; and an 75

ice support above said partition and cooperating therewith to form passages for the flow of air from said openings toward said central opening; the ice support above the central opening in said partition having a portion extending downwardly into and substantially throughout the path of the air streams emerging from said passages, whereby to deflect said air streams downwardly toward said central opening before their confluence.

8. An ice refrigerator comprising a cabinet having a partition therein subdividing the interior of said cabinet into an ice compartment above and a storage compartment below; said partition being provided with a central opening for the down flow of cold air and being spaced

from the interior sides of said cabinet to provide openings for the upflow of warm air; an ice support above said partition comprising two similar side elements formed with a plurality of ridges therein with comparatively deep valleys between said ridges and cooperating with said partition to form passages for the flow of air from said side openings toward said central opening; the central portion of said ice support comprising downwardly inclined portions spaced from the ends of and extending transversely of said passages whereby to deflect the air emerging from said passages downwardly toward said central opening to a zone of confluence.
